(57) **CLAIM**

The ornamental design for a motor vehicle and/or toy replica thereof, as shown and described.

DESCRIPTION

FIG. 1 is a left, front perspective view of a motor vehicle and/or toy replica thereof showing my new design;

FIG. 2 is a right, front perspective view thereof;

FIG. 3 is a front view thereof;

FIG. 5 is a top view thereof;

FIG. 6 is a right side view thereof; and,

FIG. 7 is a left side view thereof.

The claimed design is indicated by the relatively dark portions in the figures, while the relatively light portions are environmental and form no part of the claimed design.
